ELECTRIC WAVE-FILTER

Andreas Jaumann, Berlin-Charlottenburg, Germany, assignor to Siemens & Halske, Aktiengesellschaft, Siemensstadt, near Berlin, Germany, a corporation of Germany

Application March 21, 1932, Serial No. 600,110
In Germany March 17, 1931

9 Claims. (Cl. 178—44)

For a great many purposes in radio engineering, for instance, in broadcast reception, current smoothing means to eliminate ripples, reception in multiplex traffic along power lines by the aid of portable or transportable equipment and the like, it is desirable that the wave-filters (band-pass filters) used in connection therewith should be so adjustable that, similarly as in broadcast receiver sets, tuning to a desired frequency band should be accomplishable in a simple manner without the marginal or boundary frequencies being distorted as a result of the sloped droop of the resonance curve. In broadcast reception the demand for such a wave-filter grows with increase in the number of transmitters inasmuch as the frequency band available for any given program shrinks more and more as broadcasting stations increase in number. However, it is not only the preclusion of extraneous stations, but also the elimination of atmosphere disturbance, that makes reception appear desirable inside a sharply bounded frequency band. Now, filters have been suggested in the prior art whereby such reception is feasible. These filters consist of a plurality of oscillatory circuits of similar tuning which are in loose coupling relationship. According to one suggestion the condenser settings (controls) of the various circuits are to be mechanically inter-coupled in such a fashion that the tuning of these band filters is accomplishable by the agency of a single knob or dial. However, filters of the said sort involve the drawback that their impedance is a function of the tuning. Another fact is that only the relative channel width remains constant upon detuning, whereas the absolute channel width must be set to the desired value by varying the coupling.

The invention is concerned with a wave-filter or band-pass filter which, for a given and fixed band width, makes it possible to vary the range of transmission throughout a wide frequency range without a change in the impedance at the input or the output end being caused. The wave-filter according to the invention consists of two branches or units being at one end united directly and on the other end by way of an inductance coil or reactor. One pair of terminals (input) of this band-pass filter is constituted by the common point of the branches and the midpoint of the coil, whereas the second pair of terminals (output) is tapped on the coil upon both sides of the middle. Instead of the inductance coil (auto-transformer) it is also feasible to employ the winding of a transformer, the respective other

winding of the transformer serving as the output. Filters of this kind have been previously disclosed in U. S. Patent Number 1,882,631, though without mechanical coupling of the tuning means.

The invention will best be understood by referring to the accompanying drawing in which,

Figure 1 is a diagram of a wave filter,

Figure 2 is a side view of two variable condensers having rotors mounted on a single shaft,

Figure 3 is a detail of two rotary plates of a variable condenser, one plate being displaced slightly from the other in angular relationship,

Figure 4 is a wiring diagram of an arrangement employing an auxiliary condenser.

As shown in Fig. 1 the wave-filter consists of two impedances Z_1 and Z_2 , each one of which comprises at least a series arrangement of a coil and a condenser. Z_1 or Z_2 , or both, however, could consist also of a plurality of paralleled branches or units of this kind. In each resonance branch one element (coil or condenser) is disposed so as to be adjustable, this being insured in such a way that the setting of an element in a resonant branch is coupled with the adjustment of the element in the respective other branch or unit. If branches Z_1 and Z_2 consist of the paralleling of several series arrangements comprising coil and condenser, then a variable impedance must be provided for each one of such paralleled resonance circuits or branches.

Fig. 1 illustrates the coupled adjustment for the two condensers in Z_1 and Z_2 . Inasmuch as the condensers of the series arrangements have a group of plates at common potential they may be readily mounted upon a common spindle as shown in Fig. 2. The rotor plates of the condensers in this scheme should be preferably shaped as shown for instance, in Fig. 3 so that the capacity is inversely proportional to the square of the angle of rotation. The frequency of an associated oscillation circuit, when condensers of the said kind known in the prior art are used, will be proportional to the angle of rotation. If Z_1 and Z_2 , Fig. 1, are formed by the series arrangement of a coil and a condenser the proportions of the circuit elements can be readily indicated as illustrated by the following example. In the same, for the sake of simplicity, the assumption is made that the coils of the two branches Z_1 and Z_2 are alike and that the relative channel width is small or less than 0.1. For a given mean surge impedance of the filter (within the range of transmission) Z_0 which must be adapted to the impedance of the associated line or receiver or antenna, for an absolute channel

width $\Delta\Omega = \omega_1 - \omega_2$ and a relative channel width

$$b = \frac{\Delta\Omega}{\Omega}$$

5 there are found elements of this size:

$$L_1 = \frac{2Z_0}{\Delta\Omega} \quad C_1 = \frac{\Delta\Omega}{2Z_0\Omega^2(1-b)} = \frac{\Delta\Omega}{2Z_0\omega_1^2}$$

$$10 \quad L_2 = \frac{2Z_0}{\Delta\Omega} \quad C_2 = \frac{\Delta\Omega}{2Z_0\Omega^2(1-b)} = \frac{\Delta\Omega}{2Z_0\omega_2^2}$$

if ω_1 and ω_2 stand for resonant cyclic frequencies of the branches.

What can be inferred from these formulae is that when using constant inductances in case of 15 non-varying absolute width of range or band of the filter also the size of the surge impedance Z_0 of the filter chain inside the range of transmission remains constant.

The condition of constant absolute channel 20 width coincides with the demand that the distance or difference in resonance frequencies of the two oscillatory circuits remains always the same.

$$25 \quad \Delta\Omega = \omega_2 - \omega_1 = \left(\frac{1}{\sqrt{C_2}} - \frac{1}{\sqrt{C_1}} \right) \sqrt{\frac{\Delta\Omega}{2Z_0}}$$

$$\Delta\Omega = \omega_2 - \omega_1 = \frac{1}{2Z_0} \left(\frac{1}{\sqrt{C_2}} - \frac{1}{\sqrt{C_1}} \right)^2$$

30 If the capacity of the second circuit consists of a rotary condenser having plates of any desired shape at all ($C_2 = f(\theta)$ = angle of rotation), then in the light of the above condition the form of plates of the first condenser is given

$$35 \quad C_1 = C_2 \cdot \frac{1}{(1/\sqrt{2Z_0\Delta\Omega C_2})^2} = C_2 + \sqrt{\frac{Z_0\Delta\Omega}{2}} \cdot C_2^{3/2}$$

Since in the case of small relative channel width (and this is the case most important in practice) 40 the condenser values C_1 and C_2 differ but little from each other

$$(\sqrt{2Z_0\Delta\Omega C_2} \ll 1)$$

it will be convenient to choose two like condensers 45 C_2 , while disparity in capacity is insured by means of a small supplementary condenser in fixed coupling relationship with one of the main condensers, said supplemental condenser having this value

$$50 \quad C = C_1 - C_2 = \sqrt{Z_0 \frac{\Delta\Omega}{2}} C_2^{3/2}$$

The condition of constant channel width can be satisfied with still greater simplicity if 55 condensers are employed whose capacity grows with the reciprocal square of the angle of rotation, thus

$$60 \quad C_1 = \frac{K}{(\alpha_1 + K)^2} \quad C_2 = \frac{K}{(\alpha_2 + K)^2}$$

In the light of what precedes there is obtained in this instance:

$$65 \quad \Delta\Omega \frac{1}{2Z_0 K} (\alpha_2 - \alpha_1)^2 = \alpha_2 - \alpha_1$$

Hence, in both branches like condensers of the prescribed form of plates may be used which while displaced a constant small angle in reference to each other, are in fixed coupling relationship. (Fig. 3.)

In this embodiment moreover the absolute channel width of the filter can be varied throughout the entire coverable frequency range in a simple manner, in that the angle of adjustment 75 of the coupling is altered, though this means also

a positive change in the surge impedance of the filter-chain throughout the entire frequency band.

If several resonance branches in parallel connection are contained in the impedances Z_1 and Z_2 , then the condensers comprised in the resonant branches are subject to the identical conditions. In this instance, similarly as indicated in Fig. 4 for one branch or mesh (Z_1) it is possible by providing a small supplemental condenser which preferably consists of an adjustable auxiliary plate, to create conditions so that while in the filter the channel width and the surge impedance are preserved in rough approximation, the slope of the damping increment at 15 the boundaries of the channel may be adjusted in order that satisfactory conditions for the elimination of outer disturbances may still be made variable at will. The small auxiliary capacity C_x shown in Fig. 4, as will be noted, offers a 20 chance to shift two resonant frequencies inside the wave-filter and which are located inside the range of transmission, more or less close to the channel limits. The idea of influencing the slope of the growth in damping in this way in filters of 25 the kind as here concerned has been suggested previously in U. S. Patent 1,882,631 and U. S. patent application Serial Number 566,750. The branch z_2 must be similarly constructed and the auxiliary condenser must be mechanically inter- 30 coupled with the auxiliary condenser of branch z_1 in such a fashion that the internal resonance frequencies are symmetrically shiftable away from the center of the channel towards the marginal frequencies.

In line with what has been suggested in another application for Letters Patent Serial Number 566,750 another series branch inside z_1 or z_2 may serve the purpose of making the surge impedance not only constant, but also "evened" inside a 40 given range of transmission upon a shift of the range of transmission. The condensers of the branches or units added in that case must then likewise fulfill the mechanical conditions of coupling of the other condensers.

The tuning of the resonance branches added for the purpose of evening the surge impedance should agree with the fundamental frequencies of the range of transmission, i. e., with the tuning of the resonant branches governing the same. 50 The resonant circuits of like tuning, however, are contained in different branches z_1 or z_2 .

Instead of choosing for the condensers a suitable form of plate and instead of coupling them by a common spindle, it is also feasible to use like 55 condensers of any desired plateform in the branch pairs corresponding to each other, though in that case attention must be given so that a mechanical gearing upon turning the various condensers will satisfy the laws of capacity variation 60 previously laid down.

The connection of the branches z_1 or z_2 (see Fig. 1) or of the output must not be effected at the ends of the transformer; it is furthermore not necessary that the various resonance 65 branches in z_1 or z_2 should be tapped at the same point of the transformer. By choosing the tapping point this affords a further means to vary the surge impedance. The networks in resistance reciprocity to the filters described also allow of 70 the construction of adjustable filter-chains with constant absolute band width and constant surge impedance. However, for these forms it is preferable to choose fixed capacities and variable inductances or variometers.

I claim:

1. A band-pass filter comprising two variable reactive branches which at one end are electrically associated and at the other end united with a 5 transformer winding whose output is represented by a pair of terminals of the filter, whereas the other pair of terminals is constituted by the midpoint tap of the transformer winding and the common point of two branches, said two branches 10 comprising adjustable rotatable condensers in the respective branches, the desired tuning being effected by means of an adjustable auxiliary condenser plate connected in parallel relationship with one of the adjustable rotatable condensers 15 of said branches.
2. A band-pass filter comprising two variable reactive branches which at one end are electrically associated and at the other end united with a transformer winding whose output is represented 20 by a pair of terminals of the filter, whereas the other pair of terminals is constituted by the midpoint tap of the transformer winding and the common point of two branches, said two branches 25 comprising adjustable rotating condensers whose capacity value increases inversely proportional to the square of the angle of rotation.
3. A band-pass filter comprising two variable reactive branches which at one end are electrically associated and at the other end united with a 30 transformer winding whose output is represented by a pair of terminals of the filter, whereas the other pair of terminals is constituted by the midpoint tap of the transformer winding and the common point of two branches, said two branches 35 comprising adjustable rotating condensers wherein in the group of plates of each condenser is mounted upon a common spindle while the plates of the different condensers are displaced with reference to each other, a certain constant angle of rotation 40 during the joint setting of the condensers.
4. A band-pass filter comprising two variable reactive branches which at one end are electrically associated and at the other end united with a 45 transformer winding whose output is represented by a pair of terminals of the filter, whereas the other pair of terminals is constituted by the midpoint tap of the transformer winding and the common point of two branches, said two branches 50 comprising a coil connected in series with adjustable rotatable condensers wherein each group of rotatable plates of said condensers are mechanically inter-coupled for adjustment to obtain resonance in the two branches, and at least one 55 group of condenser plates having an auxiliary condenser connected in parallel relationship therewith.
5. A band pass filter having adjustable means 60 whereby a shift in range of constant absolute band transmission width the value of surge impedance within the entire coverable frequency range is preserved, said adjustable means comprising a pair of adjustable reactances connected in parallel at one end and to one input terminal 65 of the filter, the other end of said reactance connected in series with the primary of a transformer, the other input terminal of said filter being connected to a tap on said primary, the secondary 70 of said transformer being connected to the output terminals of said filter, at least one of the adjustable reactances being formed by a condenser and a coil connected in series and an auxiliary condenser connected in parallel with the condenser which is connected in series with the coil.
6. A band pass filter having adjustable means 75 whereby a shift in range of constant absolute band transmission width the value of surge impedance within the entire coverable frequency range is preserved, said adjustable means comprising a pair of adjustable reactances connected in parallel at one end and to one input terminal 80 of the filter, the other end of said reactance connected in series with the primary of a transformer, the other input terminal of said filter being connected to a tap on said primary, the secondary of said transformer being connected to the output terminals of said filter, at least one of the adjustable reactances being formed by a condenser and a coil connected in series and an auxiliary condenser having a small capacity with 85 respect to the capacity of the condenser in said reactance and connected in parallel therewith.
